METHOD OF OPERATING OIL-CRACKING RETORTS

Rollin M. Chatterton, Malden, Mass., and Walter C. Slade, Providence, R. I., assignors to Fuel Research Development Corporation, Boston, Mass., a corporation of Massachusetts

Application July 27, 1942, Serial No. 452,454

4 Claims. (Cl. 48—205)

This invention relates to externally heated retorts used in the continuous manufacture of carbureted water gas. Our present invention relates more specifically to the provision of an improved method of operation for such retorts, by which method the loss of time previously required for the removal of carbon deposited on the retort walls may be eliminated.

Our invention further relates to certain ordered procedure which will be hereinafter described and more particularly pointed out in the appended claims.

A retort adapted for the carrying out of our improved method of operation is shown in the drawing, which is a sectional front elevation of an externally heated retort. The retort comprises an inner casing 10 which is preferably enlarged downwardly and which is supplied with fragmentary refractory material C from a hopper 12 through a feed pipe 14 by a charging device 15. The refractory material C travels slowly downward through the retort during the operation thereof and is continuously removed from the lower end of the retort by a discharging device 16.

The retort 10 is enclosed within an outer casing 20, and the space between the retort 10 and the casing 20 is divided by baffles or partitions 21 into a series of heating flues 22, adapted to receive hot combustion gases or other heating media from a suitable source of supply.

An oil feed pipe 25 is inserted in the upper end of the retort 10 and extends downward into the upper portion of the refractory material, as clearly shown in the drawing. The rate of oil feed may be controlled by a suitable valve 26. A gas delivery pipe 28 is provided at the upper end of the retort 10 for removal of the carbureted water gas and other gaseous products of the retort. A steam pipe 30, controlled by a valve 31, provides for admission of steam at the lower end of the retort, for a purpose to be described.

When the retort is in operation, the refractory material C is highly heated by the external application of heat in the flues 22, and oil admitted through the pipe 25 is cracked in the presence of the heated refractory, with production of oil gases and vapors and with deposit of oil carbon on the refractory.

As the refractory material with the deposited carbon travels downward in the retort, steam is admitted through the pipe 30 and reacts with the carbon in the lower portion of the retort to produce water gas, which then passes up through the retort and refractory and is enriched and carbureted by mixture with the oil gases and vapors

produced by the cracking of oil in the upper part of the retort. The unconsumed carbon deposited on the refractory material continues to move downward and is eventually removed from the retort by the discharging device 16.

A retort having the general construction and operation above set forth is disclosed in the prior application of Chatterton and Paffen, Serial No. 332,154, filed April 20, 1940, and to which reference is made for more detailed disclosure.

In normal operation, the temperature in the oil-cracking zone is substantially below the temperature in the water-gas-making zone. Minimum operating temperatures may be around 1100° F. in the oil-cracking zone and around 1600° F. in the water-gas-making zone, with maximum temperatures in similar relation.

In the operation of a retort as above described, it is found that the greater part of the oil carbon from the cracking operation is deposited on the downwardly moving refractory. A small part of the carbon is carried upward with the water gas and oil vapors and passes out of the retort through the gas delivery pipe 28. There is a marked tendency also for the oil gases and vapors to move upward around the periphery of the retort and adjacent the inner surface of the retort wall, as passage for the gases is commonly more free and open adjacent the retort wall than in the body of the refractory material. The oil vapors coming in contact with the hot retort wall are cracked with the deposit of some carbon thereon.

Consequently, while the bulk of the oil carbon is deposited on the refractory material and some of it passes off with the gases, a considerable amount is deposited on the inner surface of the retort, as indicated at D in the drawing, and this latter deposit gradually builds up and increases in thicknesses until it interferes with the free downward travel of the refractory. Furthermore, the carbon thus deposited is a poor conductor of heat and reduces the transfer of heat to the cracking zone of the retort, with corresponding reduction in the oil-cracking capacity of the retort.

It has been found in actual practice that the carbon will accumulate on the retort wall in a matter of ten days to two weeks to such an extent as to require complete shutting down of the retort for cleaning. The usual method of removing deposited carbon from a retort wall is the so-called "scouring" operation that is in common use in coal gas plants. It consists in emptying the retort as completely as possible, and then passing air up through the retort to burn the deposited carbon from the wall. In an oil-cracking

retort, this scouring operation requires two or more days at intervals of ten days to two weeks, and during this time the retort is completely out of production. Burning the deposited carbon with air also subjects the retort walls to excessive temperature changes and endangers the retort structure.

In our improved method of operating an oil-cracking retort, we avoid this shutting down of the retort, with attendant loss of time, by proceeding in the following manner:

After the retort has been in operation in the usual way in the continuous manufacture of carbureted water gas for a relatively short period, such as three or four days, we change the method of operation by closing the valve 26 and shutting off the oil supply to the retort, and usually by increasing the supply of steam through the pipe 30. The downward feed of the refractory material is also preferably stopped or at least substantially reduced.

As the oil normally acts as a cooling medium in the upper part of the retort, the retort wall and the carbon deposited thereon become more highly heated after the oil is shut off and the upper part of the retort attains water-gas-making temperatures. At the same time, the steam rising through the retort becomes superheated. This superheated steam then directly attacks the deposited oil carbon, consuming the carbon and forming water gas therefrom, which gas passes out through the usual gas delivery pipe 28.

By continuous operation in this manner for a relatively short period, such as twenty-four hours, the oil carbon on the retort wall will be substantially consumed and the retort will then be in satisfactory condition for further manufacture of carbureted water gas. Oil is then again admitted through the pipe 25, the amount of steam admitted through the pipe 30 is somewhat reduced, and the manufacture of carbureted water gas is resumed for a further considerable period.

In this manner, carbureted water gas will be continuously produced in an externally heated retort during the major part of the time of operation, and uncarbureted water gas will be produced while the oil carbon on the retort wall is being consumed and removed.

In actual commercial operation, the retorts are commonly provided in benches of perhaps eight retorts, and our improved method may be conveniently carried out by operating successive pairs of retorts for twenty-four hour periods each in the manufacture of uncarbureted water gas and removal of deposited oil carbon from the retort wall, while the remaining six retorts are producing carbureted water gas. The volume of gas produced in a retort by each of the two methods of operation is usually substantially the same.

The heating value of the carbureted water gas as generally made in the oil-cracking retorts is considerably higher than the usual commercial standard for manufactured gas. By operating a part of the retorts in a bench to make uncarbureted water gas and mixing this with the carbureted water gas from the remaining retorts, the resulting mixed gas from all of the retorts in a bench may be made to equal any of the usual standards for the heating value of manufactured gas. During the first part of the cleaning period, the water gas continues to be enriched to a considerable extent by the vaporization and cracking of the oil already deposited in the refractory material and oil carbon at the time of closing the valve 26 in the oil feed pipe.

By operating in this manner, a bench of retorts may be operated for an indefinite period to produce a mixture of uncarbureted water gas and carbureted water gas, which mixture has characteristics suitable for commercial service.

As an alternative method of operation, enough excess external heat may be supplied to the upper part of the retort to raise the temperature of the deposited carbon to that required for making water gas without shutting off the oil feed. By passing more steam up through the retort than will react with the carbon deposited on the refractory material a portion of the excess steam will react with the highly heated deposited carbon to form water gas, thus removing the deposited carbon from the retort wall.

Having thus described our invention and the advantages thereof, we do not wish to be limited to the details herein disclosed, otherwise than as set forth in the claims, but what we claim is:

1. The method of operating an externally-heated upright oil-cracking retort which comprises moving a mass of fragmentary refractory material continuously downward through said retort, feeding oil into the upper part of said refractory mass, externally heating the retort and thereby heating said refractory to crack said oil, with deposit of oil carbon on said refractory and on the inner surface of the retort wall, admitting steam in the lower part of said retort to react with the oil carbon deposited on the refractory and to form water gas therefrom, carbureting and enriching said water gas by mixing said water gas with the oil gases and vapors produced by cracking the oil, increasing the external heat to raise the temperature of the retort wall and of the carbon deposited thereon to water-gas-making temperature when said deposit has attained a substantial thickness, and providing an increased flow of steam sufficient to effectively contact with the carbon deposited both on the retort wall and on the refractory, whereby said oil carbon on said retort wall becomes more highly heated and reacts with that part of said steam which is in excess of that which will react with the carbon deposited on the refractory to produce water gas, and said oil carbon being thereby removed from said retort wall with the production of additional water gas.

2. The method of operating an externally-heated upright oil-cracking retort which comprises moving a mass of fragmentary refractory material continuously downward through said retort, feeding oil into the upper part of said refractory mass, externally heating the retort and thereby heating said refractory to crack said oil, with deposit of oil carbon on said refractory and on the inner surface of the retort wall, admitting steam in the lower part of said retort to react with the oil carbon deposited on the refractory and to form water gas therefrom, carbureting and enriching said water gas by mixing said water gas with the oil gases and vapors produced by cracking the oil, increasing the external heat to raise the temperature of the retort wall and of the carbon deposited thereon to water-gas-making temperature when said deposit has attained a substantial thickness, reducing the rate of downward travel of the refractory material, and providing an increased flow of steam sufficient to effectively react with the carbon deposited both on the retort wall and on the refractory, whereby said oil carbon on said retort wall becomes more highly heated and reacts with that part of said steam which is in excess of that

which will react with the carbon deposited on the refractory to produce water gas, and said oil carbon being thereby removed from said retort wall with the production of additional water gas.

3. The method of operating an externally-heated upright oil-cracking retort which comprises feeding a mass of fragmentary refractory material thereto and moving said material continuously downward through said retort, feeding oil into the upper part of said refractory mass, externally heating the retort and thereby heating said refractory to crack said oil, with deposit of oil carbon on said refractory and on the inner surface of the retort, simultaneously admitting steam in the lower part of said retort 10 to react with the oil carbon deposited on the refractory and to form water gas therefrom, carbureting and enriching said water gas by mixing

said water gas with the oil gases and vapors produced by cracking the oil, shutting off the oil supply when the deposit of oil carbon on the retort wall has attained a substantial thickness but maintaining an adequate steam supply, and continuing the external heating, whereby said oil carbon on said retort wall becomes more highly heated and reacts with said steam supply to produce water gas, said oil carbon being thereby consumed and removed and said retort wall being effectively cleaned.

4. The method of operating an externally-heated retort as set forth in claim 3, in which the continuous downward feed of the refractory material is interrupted during the removal of the oil carbon deposited on the retort wall.
